LOOM

Anselm De Ghetto, Clifton, N. J., assignor to National Rubber Machinery Company, Akron, Ohio, a corporation of Ohio

Application August 3, 1940, Serial No. 350,239

2 Claims. (Cl. 139—13)

This invention relates to a loom apparatus and to a method for making fabricated tubes or the like, such as may be used, for example, as hose.

Heretofore, reinforced rubber hose has been made with a woven reinforcement on a loom (usually a vertical loom), the reinforcement being woven on a fixed spindle and drawn from the spindle as a woven tube to be later incorporated in the rubber hose.

One purpose of the present invention is to provide a method and apparatus whereby a hose may be directly fabricated upon a mandrel, the reinforcement being woven onto an inner tube of rubber or the like on the mandrel and an outer tube of rubber or the like being applied over the reinforcement and then the tube cured or vulcanized while on the mandrel on which it is fabricated.

Another purpose of the invention is to provide a horizontal loom construction.

The foregoing and other purposes of the invention are attained in the apparatus and the method illustrated in the accompanying drawings and described below. It is to be understood that the invention is not limited to the specific form thereof illustrated and described.

Of the accompanying drawings:

Figure 1 is a plan view, partly broken away, of apparatus embodying and adapted to carry out the invention.

Figure 2 is a side elevation thereof, partly broken away and partly in section and somewhat enlarged.

Figure 3 is an enlarged side elevation of the loom proper, enlarged and partly broken away and in section.

Figure 4 is an end elevation of the loom as shown in Figure 3.

Figure 5 is an enlarged detailed section along line 5—5 of Figure 4.

Figure 6 is an enlarged view illustrating the manner of fabricating a hose on a mandrel by the use of the apparatus in accordance with the invention, and

Figure 7 is a section through the tube, as it would appear along line 7—7 of Figure 6.

Referring to the drawings, the numeral 10 designates generally a loom which in its principal constructional features is substantially identical with vertical looms as heretofore constructed for fabricating tubes of textile, wire, or the like. It has in it the usual circumferentially arranged heddles 11, 11 with which are associated circumferential series of guides and tensioning devices 12, 12 over which the ends to be

woven into the fabricated tube may be trained and extended to the heddles in a known manner, as indicated in Figure 3 at 13^a, these ends preferably being extended to the tensioning devices 5 from vertically arranged tension rollers 14, 14, as indicated in Figures 1 and 2. Arranged to rotate in the loom in the usual association with the heddles 11 are a series of shuttles 15, 15, which have thereon ring-gear sectors 16, 16 which 10 are driven by a series of gears 17, 17, arranged circumferentially about the loom on shafts 18 and which shafts are driven by a series of gears 19, 19 thereon which are in turn meshed with a gear 20 attached to a center drum 21 which in 15 the particular horizontal loom apparatus herein disclosed is arranged on horizontal bearings 22, 22 to rotate about a fixed drum 23. The heddle actuating means is indicated generally at 24 and in the present construction may be identical with 20 heddle-actuating means usually used in the vertical loom. The shuttles 15, 15 may be arranged rotatably to be supported on the usual bearings 25, 25 on which they are retained for rotation by gibs 26 and, in order to further adapt this 25 construction for effective use in a horizontal position, the gibs 26 are formed with extensions 27 adapted to bear on a circumferential series of rollers 28, 28 mounted at each side of the shuttles on the loom structure. The rollers 28 cause the 30 shuttles to take a true path of rotation in the loom about a horizontal axis and without wobbling.

The loom structure 10 is set up on a specially designed base 29 for supporting it in its preferred horizontal position. This base is designed to support the usual loom structure as indicated at the points 30, 30 and 31, as by means of bolts. The outer end of the loom is supported by a special stanchion, as indicated at 32, so that there 35 will not be any unsupported overhanging load. The element 33 is the standard base of a vertical loom which is supported in a vertical position on the horizontal base 29 and affords a bracing and supporting structure for the horizontally positioned loom.

Extending through the member or element 33 is the usual loom operating shaft 34 on which is a driven gear 35 meshing with gear 36 in the usual way to rotate the drum center 21 and the 40 cam casings of the heddle-operating mechanism 24 which is all usual construction in vertical looms. Shaft 34 is geared to drive shaft 36^a which is driven as by pulley 37, belting 38, and motor-driven pulley 39 operated by motor 40. The usual manual means such as handwheel 41

is secured on shaft 36^a for operating the loom while threading the ends in the loom. Shaft 36^a has thereon a worm 42 which drives worm gear 43 mounted to revolve in base 29 which gear 43 has secured thereto a gear 44 constituting one of a series of change-speed gears 44, 45, 46, and 47, through which is driven a conveyor drive shaft 48. Gears 44 and 45 are arranged as shown best in Figure 1 to be readily removed from their shafts, as will be understood, to be replaced by other gears in order to obtain different ratios and different relative speeds of the drive of shaft 48 with respect to the drive of the loom whereby, as will appear later, different weaves or different picks of fabrication may be utilized to produce tubes of the required or desired construction. Shaft 43 is geared as at 49 to a jack shaft 50 which may have a chain and sprocket driving connection 51 which drives a sprocket 52 for operating conveyor chain 53 having thereon lugs 54, 54, which support and move the mandrel along, on which the hose is fabricated, in synchronization with the operation of the loom. The conveyor 53 is supported and guided on a frame 55 which may be arranged to be vertically adjusted by suitably well-known parallel adjusting mechanism, including hand wheel 56 operating through gearing (not shown) adjusting shaft 57 on which are spaced gears 58 along the frame which mesh with adjusting gears 59 arranged along the frame to operate a well-known type of vertical adjusting mechanism including rack and pinion means (not shown). By this means the conveyor is made adjustable to manufacture tubes or hose of varying diameters so that the lugs 54 will properly support and guide the mandrel carrying the fabricated tube as it issues from the loom.

The shuttles 15 may be used to support spools 15^a, 15^b and/or reels 15^a, 15^b which in the manufacture of composite textile and wire reinforced hose respectively contain textile and wire ends which may be extended from the spools or reels to well-known spreaders 15^c, 15^c which lay these ends indicated at 13^b, 13^c in coils about the mandrel M (see Figures 6 and 7). It will be understood that by means of the heddles the ends 13^a coming over the tensioning and guiding devices 12 of which there may be, as shown in the present loom, 336 ends, are woven between the coils of the textile or wire or both, which are laid on the mandrel M in a manner which will be understood by skilled artisans.

As best shown in Figures 6 and 7, the mandrels M, which may be quite long to make long sections of hose, may be supplied to the apparatus shown and extended into the apparatus from the left of Figure 1, having already formed thereon or applied thereto a tube of rubber R¹ which may be vulcanizable rubber or artificial or synthetic substitutes or other plastic material. The leading end of the mandrel is supported on the conveyor 53 which is suitably adjusted as to height, the length of the mandrel extending to the left of Figure 1 being supported on any suitable type of conveyor such as an endless belt conveyor (not shown). The belt conveyor may be free running (not driven).

The textile or wire ends, respectively 13^b and 13^c, from the spreaders 15^c are first coiled a short distance, usually by manual operation of the loom by wheel 41 and then the ends 13^a are threaded through the loom onto the mandrel as shown in Figure 3 and tied to the coils as will be understood by skilled artisans. The loom motor

is then started and the textile and/or wire ends 13^b, 13^c coiled onto the mandrel and ends 13^a interwoven into the structure in the manner indicated in Figure 3 onto the rubber tube R¹, the conveyor 53 being driven in any desired synchronization through the change-speed gearing 44, 45, 46 and 47 to produce a weave which may be more or less open, the ends being effectively held as applied to the tube R¹ by being somewhat embedded in the rubber or plastic material of the tube.

This method and apparatus permit forming tubes or hose which are of any given strength and resistance to crushing (as in suction hose) with economical use of textile and wire ends, the open mesh weave, as shown, allowing the rubber to flow into and through the mesh during vulcanization, so that the inner layer of rubber R¹ becomes integrated by rubber through the mesh with the outer layer of rubber R² which is applied to the fabricated tube on the mandrel after the mandrel M issues from the apparatus.

It will be understood by skilled artisans that as the mandrel having the tubes R¹ thereon with the reinforcing weave applied thereto issues from the equipment shown, the tube R² of vulcanizable rubber or other plastic material is applied and the fabricated tube thus made is vulcanized as by first wrapping the completely fabricated tube with helical wrappings of fabric to apply pressure to the tube and then the tube is placed in a vulcanizer and cured under the action of steam in the manner in which hose has been vulcanized for many many years.

It will be apparent from the foregoing description that many economies in the manufacture of hose are effected by use of the method and equipment illustrated in that the tubes may be directly fabricated upon the mandrels on which they are cured and in that more open weaves can be employed because of the effect of the ends when woven onto the inner layer of rubber R¹ embedding themselves to some extent into the rubber and thus being maintained without slippage in the positions in which the ends are woven.

The foregoing and other advantages flow from the improved equipment and method and, obviously, modifications thereof may be resorted to without departing from the spirit thereof or the scope of the appended claims.

What is claimed is:

1. A horizontal circular loom construction for weaving fabric tubes upon inflexible mandrels of predetermined length comprising a horizontal bearing structure having arranged thereon the usual heddle-operating mechanisms and including an element arranged to revolve about a horizontal axis and having thereon gearing for operating the usual revolving shuttles, the frame 55 of said loom being supported upon a horizontal base in which is supported drive mechanism for rotating said revolving element, a conveyor aligned with said loom for receiving and moving a mandrel axially through the loom, and driving connections on said base between said drive mechanism and said conveyor for driving said conveyor in synchronization with the revolution of said element whereby ends from the loom are woven onto the surface of the moving mandrel, there being removable and replaceable change-speed gearing connections between said drive mechanism and said conveyor-driving means, whereby the speed of said conveyor is variable with respect to the speed of said loom.

2. A horizontal circular loom construction for

weaving fabric tubes upon inflexible mandrels of predetermined length comprising a horizontal bearing structure having arranged thereon the usual heddle-operating mechanisms and including an element arranged to revolve about a horizontal axis and having thereon gearing for operating the usual revolving shuttles, the frame of said loom being supported upon a horizontal base in which is supported drive mechanism for rotating said revolving element, a conveyor aligned with said loom for receiving and moving

a mandrel axially through the loom, and driving connections on said base between said drive mechanism and said conveyor for driving said conveyor in synchronism with the revolution of said element whereby ends from the loom are woven onto the surface of the moving mandrel, said connections including removable and replaceable change-speed gears arranged between the loom-driving means and the conveyor-driving means.

ANSELM DE GHETTO.
